UNITED STATES PATENT OFFICE.

JOHN R. PETERSON, OF SUGAR CITY, IDAHO, ASSIGNOR TO UTAH-IDAHO SUGAR COMPANY, OF SALT LAKE CITY, UTAH, A CORPORATION OF UTAH.

SUGAR-SPRAYING APPARATUS.

Application filed April 24, 1926. Serial No. 104 490.

This invention relates broadly to sugar spraying machines, and more particularly to a simplified construction of liquid spraying apparatus for sugar machinery.

5 One of the objects of this invention is to provide a sugar spraying apparatus which is simple in its construction and arrangement and which may be manufactured and assembled at relatively small cost and has a minimum number of parts with little tendency for the parts to deteriorate under continuous use.

Another object of my invention is to provide a sugar spraying apparatus having a latch spring and latch mechanism for providing a positive lock for the runner when the same has become engaged with the timing screw of the mechanism for insuring reliable operation of the spraying apparatus.

20 Another object of this invention is to provide a sugar sprayer mechanism in which the sprayer nozzle is continuously operated by a crank and disc mechanism by adjustable means for directing the liquid spray to variable limits over the entire range of the sugar material to be washed for insuring a higher quality of the finished product.

A further object of the invention is to provide a sugar sprayer apparatus having an adjustable joint interposed between the sprayer nozzle and the driving mechanism for increasing or decreasing the speed of the sprayer nozzle at any point within the range of its path of oscillation, thereby insuring a perfectly uniform washing of the material under conditions where the distribution of the sugar in the carrier or basket may not be of uniform thickness.

25 A still further object of this invention is to provide a hollow bearing for carrying the oscillating arm of the sprayer nozzle of a sugar spraying apparatus permitting free motion of the nozzle, while preventing leakage of the sprayer fluid and prolonging the life of the tube gasket between the valve flange and the oscillating arm flange and at the same time increasing the rigidity of the oscillating arm and maintaining the flanges parallel.

30 A further object of the invention is to provide a construction of nozzle for sugar spray-

ing equipment which is provided with a perforated plate shaped and drilled on a radius which distributes equally the washing medium preventing the impinging together of the same before engaging with the surface of the material being sprayed, thereby eliminating all chance of cutting or wasting the material unnecessarily, thereby increasing the production of the washed material.

35 Still another object of the invention is to provide a construction of sugar sprayer in which a center operating shaft is journaled longitudinally of a gear casing and arranged to be rocked in either direction for admitting, on the one hand the water supply to the sprayer nozzle and on the other hand cutting off the water supply to the sprayer nozzle, the water supply being admitted to the sprayer nozzle simultaneously with the 40 engaging of the runner with the timing screw for controlling the time period during which water is supplied to the oscillating nozzle.

45 The invention will be described in more detail in the specification hereinafter following by reference to the accompanying drawings in which:

50 Figure 1 shows the sugar sprayer apparatus constructed in accordance with the principles herein, mounted on a centrifugal sugar washing machine; Fig. 2 is a top plan view of the sugar sprayer apparatus; Fig. 3 is a side elevation of the sugar sprayer equipment illustrated in Fig. 2, showing more clearly the 55 operating mechanism of the oscillating nozzle; Fig. 4 is an end elevation of the sugar sprayer equipment; Fig. 5 is a vertical transverse section through the sugar sprayer apparatus on line 5—5 of Fig. 2; Fig. 6 is a 60 longitudinal section through the sugar sprayer apparatus on line 6—6 of Fig. 2; and Fig. 7 is a similar longitudinal cross-sectional view through the apparatus illustrated in Fig. 6 but showing the measuring 65 slide bar released from the spring latch control for closing the water supply valve and preventing the water from reaching the nozzle.

70 Referring more particularly to the detailed parts of the drawings, reference character 1 designates a casing for the sugar

sprayer apparatus. The main drive shaft is shown at 2 journaled in bearing 2^a carried in one wall of the casing 1. The main shaft 2 has a drive sprocket 3 thereon over which 5 the sprocket chain 4 is engaged and may be driven from any suitable prime mover or source of power. The drive shaft 2 has a beveled pinion 5 thereon which meshes with bevel gear 6 keyed on transmission shaft 7 10 which is journaled in bearings 8 on opposite walls of the casing 1. A crank disc is carried on the outer extremity of transmission shaft 7 on the exterior of the casing 1. A crank pin 10 may be selectively positioned 15 in holes 10^a in the crank disc 9 in order to adjust the path of travel of oscillating nozzle 16. A bushing 11 surrounds the crank pin 10 and fits within the arcuate slot 13 in rocker arm 12. The rocker arm 12 may 20 be adjustably fixed or clamped to the oscillating pipe section 15 which leads to the sprayer nozzle 16, the position of this rocker arm determining the path of travel of the sprayer nozzle 16 during its oscillatory 25 movement. A pivotal connection 17 is provided between the pipe section 15 and the supply pipe line 19, the pivotal connection being established by means of an aligned abutting flange. A hollow bronze bearing 30 54 is inserted in the oscillating arm and extends into the pipe line 19 prolonging the life of the gasket 55 between abutting flanges 17 and 56 carried by the pipe section 15 and the pipe line 19 and also increases the 35 rigidity of the oscillating nozzle 16 and holds the flanges parallel. The water supply line 19 is provided with a valve 20 therein inserted adjacent the main supply pipe 21. The valve 20 is provided with a 40 valve stem 22, which has a pin and slot connection 23 at the top thereof with a crank arm 24. A shaft 25 is journaled within the gear case 1 in bearings 26 at opposite ends of the gear case and is arranged to rock 45 through given limits. A handle 27 is keyed to the shaft 25 exteriorly of the casing 1 for effecting rocking movement of shaft 25. The shaft 25 carries a small arm 28 thereon which connects through a link 29 with the 50 end of the measuring slide bar 31. The measuring slide bar 31 is pivotally mounted in the casing 1 as represented at 31^a. A slideable carriage 32 is mounted for reciprocatory movement on the measuring slide bar 31 and 55 is provided with screw threads 33 which engage with corresponding screw threads on timing screw 35 carried by shaft 36 journaled in bearings 37. A spur gear 38 is keyed to shaft 36 and meshes with drive gear 39 on main shaft 2, by which rotary power is delivered to the timing screw 35. On the end of casing 1 there is mounted by 60 means of bolts 40^a a spring latch 40 which extends vertically and is provided with a shoulder 41 for engaging the nose 43 of the 65

measuring slide bar 31 when the measuring slide bar is in its lowermost position indicated in Figs. 1, 2, 3, 4 and 6. A guide 44 is provided on the end of casing 1 for the measuring slide bar 31 which limits the 70 movement of the measuring slide bar 31 to a single vertical plane. For positively raising the measuring slide bar 31 there is provided an arm 45, shown more clearly in Fig. 5 as pivoted at 46 to the casing 1. The lever 45 engages the lower surface of the measuring slide bar 31 and tends to continuously urge the slide bar 31 in an upward direction by means of spring 49 which exerts a vertical upward movement on rod 48 which connects 75 at 47 with lever 45. The rod 48 has the lower end thereof mounted in a socket 50 establishing a guide for the lower end of rod 48. 80 The carriage 32 which reciprocates on the measuring slide bar 31 is provided with lower bearings, as illustrated and with rod member 57 which projects through a slot 58 in the measuring slide bar 31 and engages 85 spring 59. A limiting stop 34 is secured, as shown, to the measuring slide bar 31, so that in raised position, as represented in Fig. 7 where the threads 33 of the carriage 32 are 90 disengaged from the threads on timing screw 35, there is the tendency for spring 59 to continuously urge carriage 32 in abutment with the stop 34. Therefore by adjusting the position of the stop 34 on the measuring slide bar 31 the distance to which the carriage 32 is returned under the action of 95 spring 59 is directly determined. 100

The application of the sugar sprayer apparatus is illustrated more clearly in Fig. 1 where the apparatus is shown mounted upon a cylindrical casing 51 of the basket structure 52 which is centrifugally operated 105 through shaft 53.

The operation of the invention will be understood from the general arrangement illustrated in Fig. 1, where a sufficient amount of sugar known as a charge has been deposited in the basket 52 and where it is necessary to apply a given quantity of water or liquid in a given time to the sugar without wasting an unnecessary quantity of the material being sprayed. The sugar sprayer equipment of this invention accurately controls the time period of spraying and the amount of water or liquid required for the material being washed or sprayed, distributing the washing medium as required with the least possible waste. 110

When power is imparted to the sprocket chain 4 for driving the sprocket 3 oscillatory motion is imparted to the nozzle 16. By properly adjusting the angular position of the rocker arm 12 by changing the position of clamp 14 on the pipe section 15 and choosing the position of crank pin 10^a in the crank disc 9 the path of travel of the 115 120 125 130

nozzle 16 may be controlled. In the released portion of the measuring slide bar 31, illustrated in Fig. 7, crank 24 has been pushed down and valve 20 is closed cutting off supply of fluid to the oscillating nozzle 16.

In order to start the sugar sprayer the hand lever 27, shown in Fig. 4, must be moved to full line position. This movement raises crank 24 and lowers arm 28. The raising of crank 24 opens the water valve 20 and the lowering of crank 28 forces the screw threads 33 of carriage 32 which has been moved to its extreme left position under action of spring 59, to engage the threads of the timing screw 35 and the nose 43 of measuring slide bar 31 is secured in lowermost position by means of spring latch 40.

The carriage 32 thus engaged moves forward at a speed directly related to the pitch 20 of the threads 35 and the forward movement continues for a time interval during which water is continuously supplied to oscillating nozzle 16 until release finger 42 strikes spring latch 40 and moves the spring latch 40 outwardly to a position where shoulder 41 no longer engages nose 43, thereby releasing the measuring slide bar 31 which springs outwardly under the action of the potential energy stored in spring 49 at the same time that spring 59 which has been under compression, becomes effective to return carriage 32 to its extreme left position. The upward movement of measuring slide bar 31 imparts rocking motion to cranks 28 and 24 cutting off the water supply through valve 20.

The embodiment of the invention illustrated has proven very practical in construction and successful in operation, and while a specific construction has been illustrated it is to be understood that modifications in detail may be made within the scope of the appended claims without departing from the spirit of the invention.

What is claimed is:

1. A spraying apparatus for sugar machinery comprising a casing, a driving shaft journaled in said casing, an oscillating sprayer nozzle operated from said drive shaft, a pipe line for supplying liquid to said sprayer nozzle, a valve interposed in said pipe line, a timing screw journaled in said casing and driven from said shaft, an auxiliary shaft journaled in said casing and having a pair of oppositely extending crank members, one of said crank members controlling the operation of said valve and the other of said crank members, having means for engaging said timing screw for actuating said valve for controlling the flow of liquid through said pipe line to said oscillating nozzle.

2. A sprayer apparatus for sugar machinery comprising in combination a casing, a main shaft journaled in said casing, a transmission shaft driven by said main shaft, a sprayer nozzle, means interposed between said transmission shaft and said sprayer nozzle for imparting oscillatory movement to said sprayer nozzle, a liquid supply line connected with said sprayer nozzle, a valve interposed in said liquid supply line, timing mechanism in said casing, a rocker shaft journaled in said casing and levers extending in opposite direction from said rocker shaft for opening and closing said valve for controlling the supply of fluid to said sprayer nozzle.

3. A sprayer mechanism for sugar machinery comprising in combination a casing, a main driving shaft journaled in said casing, a sprayer nozzle, means extending between said main driving shaft and said sprayer nozzle for imparting oscillatory movement to said sprayer nozzle, an auxiliary shaft journaled in said casing, oppositely extending crank members keyed to said auxiliary shaft, a timing mechanism in said casing operated from said shaft, a liquid supply line, a valve interposed in said liquid supply line and connections between opposite ends of said crank members and said valve and timing mechanism for controlling the supply of liquid to said nozzle by the closing of said valve under control of said timing mechanism after the lapse of a particular time interval.

4. A sprayer apparatus for sugar machinery comprising in combination a casing, a main driving shaft in said casing, a rotary disc member actuated by said driving shaft, a nozzle for spraying liquid, a liquid supply line, a connection between said liquid supply line and said nozzle for permitting oscillatory movement of said nozzle while conveying liquid thereto, and an adjustable connecting slotted link extending between said nozzle and said disc member for defining the path of oscillatory movement of said nozzle.

5. A sprayer apparatus for sugar machinery comprising in combination a casing, a main drive shaft in said casing, a rotary disc member actuated by said drive shaft, a nozzle for spraying liquid, a liquid supply line, a connection between said liquid supply line and said nozzle for permitting oscillatory movement of said nozzle while conveying liquid thereto, a link having an adjustable collar connection with a portion of said nozzle and extending in a direction opposite to said nozzle and a slidable connection between said link and said disc for imparting oscillatory movement to said nozzle.

6. A sprayer apparatus for sugar machinery comprising in combination a casing, a main driving shaft in said casing, a rotary disc member actuated by said driving shaft, a nozzle for spraying liquid, a liquid supply line, a connection between said liquid supply line and said nozzle for permitting oscillatory movement of said nozzle while conveying liquid thereto, a link having an adjustable collar connection with a portion of said nozzle and extending in a direction opposite to said nozzle and a slidable connection between said link and said disc for imparting oscillatory movement to said nozzle.

7. A sprayer apparatus for sugar machinery comprising in combination a casing, a main driving shaft in said casing, a rotary disc member actuated by said driving shaft, a nozzle for spraying liquid, a liquid supply line, a connection between said liquid supply line and said nozzle for permitting oscillatory movement of said nozzle while conveying liquid thereto, a link having an adjustable collar connection with a portion of said nozzle and extending in a direction opposite to said nozzle and a slidable connection between said link and said disc for imparting oscillatory movement to said nozzle.

- oscillatory movement of said nozzle while conveying liquid thereto, a link member adjustably positioned over a portion of said nozzle and extending in a direction opposite to said nozzle, said link member containing an accurate shaped portion and a slidable connection between said arcuate portion and said disc member for imparting oscillatory movement to said nozzle.
10. A sugar sprayer apparatus comprising in combination a casing, a drive shaft in said casing, a rotary disc member driven by said drive shaft, a pin member carried by said disc member, a sprayer nozzle, a supply line for liquid, a rocking connection between said supply line and said nozzle and a link extending between said rocking connection and the pin member on said rotary disc, said link member being slotted to slidably engage said pin member for imparting oscillatory motion to said nozzle through a predetermined path.
15. A sugar sprayer apparatus comprising in combination a casing, a drive shaft in said casing, a rotary disc member driven by said drive shaft, a sprayer nozzle, a supply line for liquid, a rocking connection between said supply line and said nozzle and a cam member extending between said rocking connection and said rotary disc member for imparting oscillatory motion to said nozzle.
20. A sugar sprayer apparatus comprising in combination a casing, a drive shaft in said casing, a rotary disc member driven by said drive shaft, a sprayer nozzle, a supply line for liquid, a rocking connection between said supply line and said nozzle, a pin member carried by said disc member, a link member adjustably connected with said rocking connection and having a portion thereof formed in the shape of a cam for effecting oscillatory movement of said nozzle.
25. A sugar sprayer apparatus comprising in combination a casing, a drive shaft in said casing, a rotary disc member driven by said drive shaft, a sprayer nozzle, a supply line for liquid, a rocking connection between said supply line and said nozzle, a pin member carried by said disc member, a link member adjustably connected with said rocking connection and having a portion thereof cut out interiorly providing a pair of arcuate shaped sides embracing opposite sides of said pin member whereby rotary motion of said disc effects oscillatory movement of said nozzle.
30. A sugar sprayer apparatus comprising in combination a casing, a drive shaft in said casing, a rotary disc member driven by said drive shaft, a sprayer nozzle, a supply line for liquid, a rocking connection between said supply line and said nozzle, a pin member carried by said disc member, a link member adjustably connected with said rocking connection and having a portion thereof cut out interiorly providing a pair of arcuate shaped sides embracing opposite sides of said pin member whereby rotary motion of said disc effects oscillatory movement of said nozzle.
35. A sugar sprayer apparatus comprising in combination a casing, a drive shaft in said casing, a rotary disc member driven by said drive shaft, a sprayer nozzle, a supply line for liquid, a rocking connection between said supply line and said nozzle, a pin member carried by said disc member, a link member adjustably connected with said rocking connection and having a portion thereof cut out interiorly providing a pair of arcuate shaped sides embracing opposite sides of said pin member whereby rotary motion of said disc effects oscillatory movement of said nozzle.
40. A sugar sprayer apparatus comprising in combination a casing, a drive shaft in said casing, a rotary disc member driven by said drive shaft, a sprayer nozzle, a supply line for liquid, a rocking connection between said supply line and said nozzle, a pin member carried by said disc member, a link member adjustably connected with said rocking connection and having a portion thereof cut out interiorly providing a pair of arcuate shaped sides embracing opposite sides of said pin member whereby rotary motion of said disc effects oscillatory movement of said nozzle.
45. A sugar sprayer apparatus comprising in combination a casing, a drive shaft in said casing, a rotary disc member driven by said drive shaft, a sprayer nozzle, a supply line for liquid, a rocking connection between said supply line and said nozzle, a pin member carried by said disc member, a link member adjustably connected with said rocking connection and having a portion thereof cut out interiorly providing a pair of arcuate shaped sides embracing opposite sides of said pin member whereby rotary motion of said disc effects oscillatory movement of said nozzle.
50. A liquid spraying apparatus for sugar machinery comprising in combination a casing, a main drive shaft journaled in said casing, an oscillating nozzle driven by power delivered through said drive shaft, a liquid supply line connected with said oscillating nozzle, a valve positioned in said liquid sup-
- ply line, a timing screw journaled in said casing, a measuring slide bar pivoted at one end to said casing and carrying a slide carriage thereon for engagement with said timing screw, a bell crank connected at one end with said valve and at the other end with the outer extremity of said measuring slide bar, a spring latch for normally holding said measuring slide bar in lowermost position with said carriage, while maintaining said valve in open position, and in engagement with said timing screw, and an arm secured to said carriage for disengaging said latch from said measuring slide bar at the end of its path of travel for closing said valve.
55. A liquid spraying apparatus for sugar machinery comprising in combination a casing, a main driving shaft journaled in said casing, a sprayer nozzle, means for imparting oscillatory motion to said sprayer nozzle from said main driving shaft, a timing screw, a measuring slide bar pivotally mounted in one side of said casing and normally spring pressed in an upward direction, a spring latch for engaging the outer extremity of said measuring slide bar for maintaining said measuring slide bar in a plane extending parallel to the axis of said timing screw, a carriage mounted upon said measuring slide bar for normally engaging said timing screw when said spring latch is secured over said measuring slide bar and an arm member secured to said carriage for abutting and disengaging said spring latch from said measuring slide bar by pressure directed against said spring latch and correspondingly disengaging said carriage from said timing screw.
60. A liquid spraying apparatus for sugar machinery a combination of a spraying nozzle and means for governing the supply of liquid to said nozzle comprising a timing screw, a measuring slide bar, a slide carriage mounted thereon, a spring latch for locking said bar into such position that said carriage engages said timing screw, a spring member for normally tending to disengage said carriage from said timing screw, and a substantially horizontal member projecting from said carriage for establishing an abutment with said spring latch when said carriage is driven to the end of its path of travel for disengaging said spring latch from said measuring slide bar whereby said bar is moved upwardly under the action of said spring member disengaging said carriage from said timing screw.
65. In a sugar spraying apparatus, a casing, a liquid spraying nozzle arranged for oscillatory motion, a timing screw for controlling the movement of said liquid spraying nozzle, a measuring slide bar pivotally mounted over said timing screw and having a carriage mounted thereon for reciprocatory movement, a flat spring member carried

by said casing adjacent the extremity of said measuring slide bar, a nose formed on said measuring slide bar and a shoulder formed on said flat spring member, said shoulder 5 engaging said nose for holding said carriage into engagement with said timing screw and an arm secured to said carriage for engaging said flat spring member and moving the

same out of engagement with said nose when said carriage approaches the end of its path 10 of travel whereby said carriage may be moved out of engagement with said timing screw.

In testimony whereof I affix my signature.

JOHN R. PETERSON.
